UNITED STATES PATENT OFFICE.

CHARLES HANSEN AND ARTHUR D. ZIEBARTH, OF DAVENPORT, IOWA, ASSIGNEES TO DAVENPORT MACHINE AND FOUNDRY COMPANY, OF DAVENPORT, IOWA, A CORPORATION OF IOWA.

ADJUSTING MEANS FOR JOLT STRIPPER MACHINES.

Application filed October 30, 1924. Serial No. 746,823.

Our invention relates particularly to the adjustment of the relative positions of the stripper means whereby they may be caused to commence lifting the opposite sides of the form simultaneously so that there may be a minimum amount of cracking of the mold, when removing it from the pattern, and among the objects of our invention are to provide means in a jolt stripper machine 5 for so adjusting the stripper mechanism that the two sides thereof will begin lifting the form at the same time; to provide adjusting means for the stripper mechanism; to provide a novel form of adjusting means 10 for a machine of the character described; to improve upon the construction of the stripper mechanism; and such further objects, advantages and capabilities as will later more 15 fully appear and as are inherent in the construction disclosed.

Our invention further resides in the combination, construction and arrangement of parts illustrated in the accompanying drawing and, while we have disclosed herein a 20 preferred form of our invention, we desire the same to be understood as illustrative only and not as limiting said invention.

In the drawing annexed hereto and forming a part hereof, Fig. 1, is a lateral elevation of a jolt stripper machine showing the location of our adjusting means; Fig. 2 is an end elevation of this machine showing the relative positions of the co-operating stripper pistons; Fig. 3 is a fragmentary elevation of a portion of the mechanism shown in Fig. 1; Fig. 4 is an edge view of the mechanism in Fig. 3; and Fig. 5 is a view similar to Fig. 3 showing a modified form of adjusting means to be used, if desired, in substitution for that shown in the other figures.

Referring more in detail to the annexed drawing, numeral 1 designates generally the body of the jolt stripper machine which is 45 preferably mounted upon wheels 2 for ease in transportation from one location to another. At the top of the body is a table 3 upon which the pattern is placed when it is desired to pack the sand around the pattern. In use, the form is also placed upon this table, surrounding the pattern, and sand is then filled in between the pattern and form as is understood by those experienced 50 in this art.

At opposite sides of the table 3 are located the stripper pistons 4 and 5 having stripper heads 6 and 7 by means of which the mold is lifted from the pattern after the sand has been packed around the latter. A shaft 8 is mounted in bearings 9 upon 60 the machine and carries adjacent its opposite ends a pair of crank arms 10 and 11. These crank arms are pivotally connected at 12 to the links 13 and 14 which are in turn pivotally connected at 15 to the stripper 65 heads 6 and 7.

The link 13 is provided in its lower end with an opening 16 for the reception of an adjustable block 17 having therein an opening 18 for the reception of the pivot connecting the crank arm 10 and the link 13. The sides of the opening 16 are formed as slideways for the block 17 so that the same will be properly guided and held in position therein. An adjusting bolt 19 has 75 screw threaded engagement with an opening in the arm 13 and is locked in position by means of a locknut 20. The head of this bolt engages one face of the block 17 and a similar bolt 21 engages the opposite face 80 thereof, as shown in Figs. 3 and 4. The bolt 21 has a locknut 22 which engages the cross-head 23 to hold the bolt in adjusted position.

Instead of the construction described 85 above the block 17 may have inclined sides 24 as shown in Fig. 5 and blocks 25 having similarly inclined sides will co-operate therewith to move the block 17 upwardly or downwardly as desired, when the bolts 26 90 are properly manipulated. These bolts will be held in position by lock nuts 27 or other desired securing means. The crosshead 23 is secured in place by bolts 28 or other suitable means.

From the construction described above, it 95 will be apparent that the stripper heads 6 and 7 may be relatively adjusted, vertically, so that they will engage the form on the table 3 simultaneously, thereby causing opposite sides of the same to move upwardly at the same time, thus reducing to a minimum the amount of disturbance and cracking of the mold, when removing the mold from the pattern. The shaft 8, crank arms 10 100 and 11, and links 13 and 14 cause the movements of the pistons 4 and 5 to synchronize, while the adjustability of the block 17 makes 105

it possible to cause the stripper mechanism to begin lifting on opposite sides of the form at the same time. From the foregoing it will be seen that we have provided a novel means for accomplishing the objects herein specified.

Having now described our invention, we claim:

1. In a machine of the character described, having pattern supporting means and means movable to strip a mold from a pattern, said last named means comprising a plurality of separate parts engaging the mold supporting form at separated points, independent hydraulic means for operating the said separate parts, means for preventing one side of the stripping means from advancing more rapidly than the other, and means for relatively adjusting opposite sides of said preventing means.
2. In a stripping mechanism, reciprocable stripping means, independent hydraulic means on opposite sides of the machine for operating the stripping means, mechanism for controlling the functioning of the stripping means so that opposite sides will oper-

ate synchronously, and means for adjusting the last named means to cause opposite sides of the stripping means to begin functioning at the same time.

3. In a stripper mechanism, a table, stripper pistons on opposite sides thereof, links and connecting means therefor to synchronize the movements of the stripper pistons, and means for adjusting the relative heights of the pistons.

4. In a jolt stripper machine having a table, independent stripping members on opposite sides thereof, means to raise the stripping members, and means connecting the raising means so that they will operate synchronously; an adjustable trunnion joining the stripping-member raising-means and the connecting means, and adjusting means whereby the trunnion may be adjusted to cause the stripping members to begin functioning simultaneously and to operate synchronously.

In witness whereof, we hereunto subscribe our names to this specification.

CHARLES HANSEN.
ARTHUR D. ZIEBARTH.
